UNITED STATES PATENT OFFICE

2,522,210

PORTABLE ALTAR CONSTRUCTION

Emanuel I. Cohen, Philadelphia, Pa.

Application June 9, 1947, Serial No. 753,563

2 Claims. (Cl. 312—33)

2

This invention relates to an altar construction and more particularly to a portable, foldable and collapsible altar. Among the general objects of the invention are to provide such a device which is light in weight and compact in form so as to be readily portable, erectable and disassembled by one man. To this end the altar is made as a single unit, the several parts thereof being secured together, all being within the reach and control of a man for erection or disassembly, either of which may be completely accomplished with a few swift, easy movements. Such an altar is desirable among roving missionaries, in churches and in the military and naval forces. A primary consideration among these services are the features of portability, including lightness and compactness, so that such an altar can be quickly erected for services in the field or on a ship, and as quickly dismantled and packed away or moved to one side, as the occasion or the dictates of necessity may require.

An additional object is to provide an altar which will be acceptable to the followers of different faiths and in furtherance of this object the altar is provided with a front panel wherein a cross is removably secured so that it may be quickly removed for the substitution of a star of David, or other emblem of a different religious faith.

Another object of the invention is to provide such an altar having a table and a collapsible retable thereon.

Another object is to provide such an altar having a front and side walls and table, the side walls and table being pivoted to the front in such a manner as to be collapsible with respect to said front when the device is not in use.

Another object is to provide a retable for such an altar in which said retable is collapsible so as to lie substantially parallel to said table and on the undersurface thereof when not in use and to be erectable as a ledge on said table when the altar is set up for worship.

A further object is to provide a retable which is pivoted to a free edge of the table proper, said retable comprising front, rear and top sections and end walls, all hingedly connected together, the end walls being hinged to the central or top section, said sections having fastening means cooperating with corresponding means on said end walls for locking said sections together when they are erected on said table.

For the accomplishment of these and such other objects as may hereafter appear, the invention is more fully developed in the following specification

and detailed description, reference being had to the drawings in which:

Figure 1 is a perspective view of the erected altar.

Figure 2 is a rear view thereof, with the table in raised position, showing the means for securing the several parts together.

Figure 3 is a front elevation of the altar with the side walls extended in supporting position,

10 showing the table and retable in collapsed position.

Figure 4 is a perspective view showing the table being lowered into assembled position, with the retable partially assembled.

Figure 5 is a plan view of the altar showing it in collapsed condition.

Figure 6 is an end view of the altar in collapsed condition.

Figure 7 is a plan view of the altar with the

20 table removed and one corner of the front wall cut away to show the arrangement and construction where the side wall joins the front.

Figure 8 is a detail of the latch construction

used to lock the parts together in erected or col-

25 lapsed condition.

The altar comprises generally a sheet metal

construction, preferably of light weight, such as

aluminum, having a front wall 10, side walls or

wings 11, 11a, a table 12 and a retable generally

indicated by 13. The front wall is trimmed to

give a panelled effect and is suitably embellished

30 by a centrally disposed, embossed panel 15 in

which a cross 16 is removably mounted for op-

tional substitution of a star of David, as shown in

35 dotted lines in Figure 2, or for the emblem of some

other religious faith or order.

The altar is of pressed sheet metal construction

throughout, the parts being welded wherever pos-

30 sible, and may be finished in any suitable manner,

40 a mahogany grained finish lending itself well to

the structure for religious purposes and being gen-

erally acceptable.

The front wall 10 has its side edges bent into

flanges 18 (only one of which is shown, Figure 7),

45 extending rearwardly at an angle of substantially

90° and corner posts 19, 19a resembling side rails

are secured to these flanges by welding, riveting

or otherwise. On its inner side wall, spaced from

the edge thereof, each corner post supports angle

50 members 20, 20a and the hinges 21, 21a, respec-

tively, for the side walls carried by these angles

as shown in Figure 7. The angles 20, 20a are

spaced slightly from the edge of the corner post

in order that the side wall may be fitted into said

post to give said wall a panelled effect, its remain-

ing edges and base being suitably trimmed to match the trim of the front panel, the trim being accomplished by pressing the metal as desired, or by assembling it in any other suitable manner known to those skilled in the art.

The front wall is provided with a forwardly extending overhanging lip 22 along its upper edge and the table 12 is hinged to this lip, which extends forwardly a distance equal at least to the thickness of the table, so that when the latter is collapsed against the front wall, the top surface 12a thereof will be substantially parallel to said wall. The table is hinged to this lip by hinges 1, 1a.

The retable 13 is hinged to the opposite edge of said table at 23, 23a and comprises a front and rear section, 13a, 13b, respectively, hingedly connected together at 13a' and 13b', respectively, by a top section 13c. The three sections are rigidly joined together, when erected, by end walls or flaps 13d and 13e which are hinged to the ends of the top section. Suitable toggle latches 24 and hooks 25 are provided at the adjoining edges of said sections and end walls so that they may be securely fastened together when the retable is erected. Similar latches are secured to the free ends of the side walls, and similar hooks are affixed to the inner side of the front wall and to the underside of the table so that said side walls may be securely latched parallel to said front wall when the altar is collapsed, and latched to the table when released from the front wall as the altar is erected.

The side walls are additionally braced with respect to the front 10 and table 12 by pins or dowels 28, 28a which project from the upper surfaces of said side walls into sockets 29, 29a, respectively, formed in the underside of the table to receive them when the altar is erected. Also, braces 30, 30a, suitably pivoted to the rear face of the front wall, engage the side walls adjacent their bottom edges when the altar is erected, these braces being held flush against the inner face of the front wall by spring clips 31, 31a, respectively, when the altar is collapsed.

The cross, star of David, or other religious emblem may be provided with stud screws 26 on their rear faces and these screws extend through corresponding holes provided therefor in the face of the embossed panel 15. Either emblem may thereupon be optionally secured in place by suitable wing nuts 27 as occasion demands.

When carried in the field, the altar is dismantled or collapsed as shown in Figure 6 and is placed in a suitable canvas carrying case (not shown) by means of which it may be readily moved from place to place by one man. To use it, the altar is raised into the position shown in Figure 6, the side walls 11, 11a are swung outwardly as shown in Figure 7, and the braces 31, 31a are swung out from the front wall and secured thereto. The retable is next unlatched from the underside of table 12 and swung up-

wardly as shown in Figure 4, at the same time swinging table 12 about its hinges 1, 1a to bring it to rest on the side walls, with the pins thereon engaging their corresponding sockets in the underside of the table. The retable is then completely assembled as a ledge on said table and the parts thereof securely latched together. The altar is then ready for the disposition of the religious paraphernalia and prayer books thereon.

10 To dismantle and collapse the altar, the procedure just described is reversed.

Having thus described my invention, what I claim as new and desire to protect by Letters Patent is:

15 1. A portable, collapsible sheet metal altar comprising a front and side walls and a table therefore, said walls and table being pivoted to said front so as to lie substantially parallel thereto when collapsed, and being swingable about their

20 respective pivotal axes to assume side wall and table positions when erected for use, said front and said table having hooks secured thereto, and latches secured to said side walls, said latches engaging the hooks of said front wall when the

25 structure is collapsed and engaging the hooks of said table when the structure is erected, the parts thereby being locked against movement in either collapsed or erected position.

2. A portable, collapsible altar comprising a front having flanged side edges, a post adjacent each of said edges, each post having parallel flanges, the innermost flange of each being secured to the respective adjacent flange of said front, the outermost flange of each post being of

30 greater width than the innermost flange and having an angle member secured thereto spaced from the free edge thereof, a side wall for said altar hinged to each angle iron, each wall overlapping the respective adjacent outermost flange

35 so as to present an unbroken surface when the altar is erected, said front having a lip overhanging its upper edge and a table pivoted to said lip, and resting on said front and side walls when the altar is erected for worship.
